W. H. MEYER,
CLOTHES WRINGER,

APPLICATION FILED FEB. 7, 1920.

1,401,805.

Patented Dec. 27, 1921.

UNITED STATES PATENT OFFICE.

WILLIAM H. MEYER, OF ST. LOUIS, MISSOURI, ASSIGNOR, BY MESNE ASSIGNMENTS,
TO THE DAVIS SEWING MACHINE COMPANY, A CORPORATION OF DELAWARE.

CLOTHES-WRINGER.

1,401,805.

Specification of Letters Patent. Patented Dec. 27, 1921.

Application filed February 7, 1920. Serial No. 357,052.

To all whom it may concern:

Be it known that I, WILLIAM HENRY MEYER, a citizen of the United States of America, a resident of the city of St. Louis, 5 in the State of Missouri, have invented certain new and useful Improvements in Clothes-Wringers, of which the following is a full, clear, and exact description, reference being had to the accompanying drawings, forming a part of this specification.

This invention relates to improvements in clothes wringers, the main object being to produce a strong and simple wringer structure provided with a simple releasing device 15 whereby the pressure at the wringer rolls may be easily and quickly released.

Figure I is a front elevation, partly in section, illustrating a wringer embodying the features of this invention.

Fig. II is a vertical section taken approximately on the line II—II of Fig. I.

To illustrate the invention I have shown a wringer frame comprising upright end members 1 forming housings for the bearings 2 and 2' in which the wringer rolls 3 and 3' are rotatably mounted, said rolls being provided at their ends with journals engaging the bearings 2 and 2' respectively. The wringer frame also includes horizontally disposed upper members 4 integrally connected to the upright members 1.

Compression springs 5 are interposed between the upper bearings 2 and a tie-bar 6. Screws 7, acting upon end portions of the tie-bar 6, may be adjusted to vary the pressure of the springs 5. These springs allow the upper roll 3 to move toward and away from the lower roll and they tend to force the upper roll into engagement with the lower roll.

To illustrate the preferred form of the invention I have shown a thrust-receiving bar 8 arranged between the rigid frame members 4 and located immediately above the tie-bar 6. Nuts 9 are secured to the end portions of the thrust-receiving bar 8 to receive the adjusting screws 7. It will now be understood that the spring pressure is transmitted through the end portions of tie-bar 6 to the lower portions of screws 7, and thence to the nuts 9 in the thrust-receiving bar 8. If the bar 8 is held in a fixed position, the springs 5 will be retained under pressure, and the screws 7 may be adjusted to vary the

pressure. However, if the thrust-receiving bar 8 is released, and permitted to move vertically, the spring pressure will be immediately relieved, and the upper wringer roll 3 can then be freely moved away from the lower roll.

I will now describe the breakable bridge which engages the top face of the thrust receiving bar 8 to normally retain said bar in a fixed position. This bridge preferably comprises a pair of abutment wings 10 located between the upper frame members 4 and pivotally connected thereto as shown at 11, said frame members 4 being slotted to receive pivot loops which extend from the wings 10, and the axes of the pivots being 60 parallel with the wringer rolls. Each wing 10 is approximately L-shaped in cross section to provide a horizontal abutment face engaged by the thrust-receiving bar 8, and an upwardly extending flange adapted to be 65 engaged by a releasing clip, as will be presently described.

The wringer frame preferably includes an upper rigid frame member 12, located between the frame members 4 and having its 80 ends rigidly attached to the upright frame members 1. The releasing clip is in the form of a lever pivoted at 13 to the rigid frame member 12 and provided with a forked lower end 14 straddling the upper portions of the wings 10. This lever has an operating handle 15 which may be depressed to release its forked end 14 from the wings 10. 16 designates a spring tending to retain the lever in the position shown in the drawings. The 85 rigid upper frame member 12 lies between the wings 10, and the clip formed by the forked end 14 co-operates with the wings 10 to form a transverse bridge which extends across the upper portion of the wringer frame. This bridge is normally subjected to the spring pressure which tends to throw the thrust-receiving bar 8 in an upward direction. To break the bridge, it is only necessary to depress the releasing member 15 90 (Fig. I) thereby releasing the fork or clip 14 from the wings 10. In this event, the pressure transmitted through the thrust-receiving bar 8 will cause the wings 10 to turn on their pivots, and the upper edges of the 95 wings will move as indicated by arrows in Fig. II so as to engage the frame members 4 which limit the motion of the wings, and

which permit said wings to serve as stops for limiting the upward motion of thrust-bar 8.

I claim:

- 5 1. In a wringer, a frame, a pair of wringer rolls, yielding means for forcing one of said rolls toward the other, a movable thrust-receiving member mounted in said frame and subjected to the pressure of 10 said yielding means, and a breakable bridge extending across said frame and coöperating with said movable thrust-receiving member to retain said yielding means under pressure, said breakable bridge including a pair of 15 wings, a pressure releasing device spanning the inner margins of said wings and pivots connecting the outer margins of said wings to said frame, the axes of said pivots being approximately parallel with the axes of said 20 wringer rolls.
2. In a wringer, a frame, a pair of wringer rolls, yielding means for forcing one of said rolls toward the other, a movable thrust-receiving member subjected to 25 the pressure of said yielding means, and a breakable bridge extending across said frame and coöperating with said movable thrust-receiving member to retain said yielding means under pressure, said breakable bridge 30 comprising a pair of wings pivoted to said frame, the axes of the wing pivots being approximately parallel with the axes of said wringer rolls, and a pressure releasing clip uniting said wings to prevent breakage of 35 said bridge.
3. In a wringer, a frame, a pair of wringer rolls, yielding means for forcing one of said rolls toward the other, a movable thrust-receiving member subjected to 40 the pressure of said yielding means, and a breakable bridge extending across said frame and coöperating with said movable thrust-receiving member to retain said yielding means under pressure, said breakable bridge 45 comprising a pair of wings, L-shaped in cross section, pivots securing said wings to said frame, the axes of said pivots being approximately parallel with said wringer rolls, and a pressure releasing clip connecting said 50 wings to prevent breakage of said bridge.
4. In a wringer, a frame, a pair of wringer rolls, yielding means for forcing one of said rolls toward the other, a movable thrust-receiving member subjected to the

pressure of said yielding means, and a 55 breakable bridge spanning said frame and coöperating with said movable thrust-receiving member to retain said yielding means under pressure, said breakable bridge comprising a pair of elongated wings pivoted to 60 said frame and having upturned flanges at their adjacent margins, said frame having a rigid member located between said flanges, and a clip pivoted to said rigid member and uniting said wings to prevent breakage of 65 said bridge.

5. In a wringer, a frame, a pair of wringer rolls, yielding means for forcing one of said rolls toward the other, a movable thrust-receiving member subjected to the 70 pressure of said yielding means, a transverse bridge spanning said frame and coöperating with said movable thrust-receiving member to retain said yielding means under pressure, said transverse bridge comprising a pair of wings pivotally secured to 75 said frame and a retaining clip pivoted to said frame and engaging said wings to prevent breakage of said transverse bridge, and an operating member associated with said retaining clip by which to remove said clip from said wings.

6. In a wringer a frame comprising upright end members, horizontally disposed upper members uniting said end members 85 and an intermediate member between said upper members, all of said members being rigidly secured together, wringer rolls, yielding means forcing one of said rolls toward the other, a movable thrust-receiving member subjected to the pressure of said 90 yielding means, and a breakable bridge spanning the space between said upper members and coöperating with said movable thrust-receiving member to retain said yielding means under pressure, said breakable bridge comprising wings located at opposite 95 sides of said intermediate member and pivoted to said upper members, and a clip pivoted to said intermediate member and 100 straddling said wings to prevent breakage of said bridge, said clip having an operating member whereby it may be released from said wings.

In testimony that I claim the foregoing I 105 hereunto affix my signature.

WILLIAM H. MEYER.
